UNITED STATES PATENT OFFICE.

JOHN L. RUSSELL, OF PELLA, IOWA.

IMPROVEMENT IN COTTON-SEED PLANTERS.

Specification forming part of Letters Patent No. 56,274, dated July 10, 1866.

To all whom it may concern:

Be it known that I, JOHN L. RUSSELL, of Pella, Marion county, State of Iowa, have invented a new and Improved Cotton-Planter; and I do hereby declare that the following is a full, clear, and exact description thereof, which will enable others skilled in the art to make and use the same, reference being had to the accompanying drawings, forming part of this specification, in which—

Figure 1, Sheet 1, shows a top plan of my invention. Fig. 2 is a vertical longitudinal section taken in the line $x x$, Fig. 1. Fig. 3, Sheet 2, is a cross-section taken in the line $y y$, Fig. 2; and Figs. 4 and 5 are detail views.

This invention relates to new and useful improvements in cotton-planters; and the invention consists in a machine or vehicle having an adjustable wedge-shaped furrower, which opens the tops of the ridges or drills in advance of the seed-dropping devices, the said furrower being provided with a rotating cutter upon its front edge for clearing trash and like obstructions, and having a self-adjusting covering-roller for closing the furrows, and also seed dropping or delivering rollers of improved construction, with other minor improvements, as hereinafter explained.

A A' A² a, Fig. 2, in the accompanying drawings, is a frame-work mounted on wheels B B, and having a fixed hopper, L, with a second hopper, I, hinged to the frame-work above by hinge r, and a third hopper or section, M, hinged to the frame below by hinges s, all of these sections forming a single hopper, which contains two feeding or delivering cylinders, C D.

F is a wedge-shaped furrow-opener, (see also F, Fig. 3,) having a rotating cutter, f, in its wedge nose or front, and is suspended in an adjustable manner vertically by two set-screws, H H.

g g are studs projecting upward from F and working in guides G G, so as to steady F in its position.

The furrower F has also a tooth, m, on each side and in the rear of the delivering-throat M, for the purpose of loosening up the dirt before the covering-roller N.

The furrow closing or covering roller N is pivoted to the bottom of a vertical sliding

frame, n, and when resting on the crest of the ridges and when covering it adjusts or regulates its own height by sliding vertically.

The roller and frame N n may be thrown up when desirable by the elevating-lever q.

p (see also p, Fig. 1) is a knife or scraper, which is pivoted at one end to the frame n, while the other end plays vertically in a guide, P, as shown in Fig. 1, and its office is to scrape dirt off the covering-roller N, Fig. 2, and keep said roller clean. l is a chain which limits the drop of the covering-roller.

The supporting-wheel B' has a driving-gear wheel, b, fitted on its hub on the inside of the wheel, and this gear-wheel b engages with a pinion, c, to drive the upper feed-roller, C, Fig. 3, and also engages with a second pinion, e, to drive the lower feed-roller, D. These rollers C and D have flaring ends c' c' d' d', and are also armed with spikes c² and d, which carry the seed through the hopper, so they are delivered or dropped into the furrow with a constant and even flow.

The bearings K, Fig. 5, of the lower feed cylinder or roller are secured to the framework by bolts k k, which pass through slots in K and allow the said bearing K to be moved endwise by means of a lever, j, and connecting-rod J, Fig. 4, so that the pinion e is thrown out of gear or disengaged from the driving-gear b, and the action of the roller D suspended at will.

The machine is provided with pinions c and e, and with sliding bearings K and disengaging devices on both sides of the machine, so that the driving-wheel B' may be changed to work with equal facility on either side.

The upper section, I, of the hopper or seed-box has a platform, i, attached, which affords a seat for the driver or operator.

Its operation is as follows: T, Fig. 3, shows a cross-section of one of the ridges or drills in which the seed is deposited. The opener F is adjusted to a proper height by the set-screws H H, so as to enter the drill to a proper depth, and the furrows are formed in the top of the ridge as the machine progresses, and the seed is dropped regularly into the furrow and covered by the action of the teeth m and the closing-roller N, which brings up the rear. Owing to the rough and fuzzy nature of cotton-seed,

it is a point of some nicety to get the seed to flow with sufficient regularity; but this is fully obviated by the use of the toothed rollers, which feed from one to the other, and the lower roller dropping the seed.

Having thus described my invention, what I claim as new, and desire to secure by Letters Patent, is—

1. The wedge-shaped furrow-opener F, suspended in an adjustable manner by steadyng-studs g g and adjusting-screws H H, and having a rotating trash-cutter, f, substantially in the manner and for the purpose set forth.

2. The teeth or small shovels m, in connection with and occupying a position between

the furrow-opener F and the closing-roller N, substantially as and for the purpose described.

3. The toothed rollers C and D, with or without the flaring ends c' c' d' d', arranged one above the other in the seed-box, and operating as shown and explained, substantially in the manner and for the purpose specified.

4. The sliding roller and frame N n, scraper p, elevating-lever q', and stop-chain l, arranged and operating as shown and explained.

JOHN L. RUSSELL.
